DESIGN FOR A TIRE

Albert Hargraves, Akron, Ohio, assignor to The Firestone Tire & Rubber Company, Akron, Ohio, a corporation of Ohio

Application June 13, 1934, Serial No. 52,161

Term of patent 14 years

To all whom it may concern:

Be it known that I, Albert Hargraves, a citizen of the United States, residing at Akron, in the county of Summit and State of Ohio, have invented a new, original, and ornamental Design for a Tire, of which the following is a specification, reference being had to the accompanying drawing, forming a part thereof:

In the drawing:

I claim:

The ornamental design for a tire as shown.

ALBERT HARGRAVES.
